US0D1097337S

(12) **United States Design Patent** (10) **Patent No.:** **US D1,097,337 S**
(45) **Date of Patent:** **** Oct. 7, 2025**

(54) **HARNESS**

(71) Applicant: **ZEDEL**, Croles (FR)

(72) Inventor: **Paul Petzl**, Barraux (FR)

(73) Assignee: **ZEDEL**, Croles (FR)

(**) Term: **15 Years**

(21) Appl. No.: **29/861,538**

(22) Filed: **Nov. 30, 2022**

(30) **Foreign Application Priority Data**

May 30, 2022 (EM) 009046600-0001

(57) **CLAIM**

The ornamental design for a harness as shown and described.

DESCRIPTION

FIG. 1 is a front elevational view of a harness, showing the new design;

FIG. 2 is an enlargement of area 2 in FIG. 1; and,

FIG. 3 is a front, left-side perspective view thereof.

The broken lines depict parts of the harness that form no part of the claimed design. The dot-dash chain lines depict areas of enlargement and form no part of the claimed design.

1 Claim, 3 Drawing Sheets
